UNITED STATES PATENT OFFICE.

GEORGE C. CASSADA, OF GALION, OHIO, ASSIGNOR TO THE GALION IRON WORKS & MFG. CO., OF GALION, OHIO, A CORPORATION OF OHIO.

ROAD SCARIFIER.

Application filed December 12, 1923. Serial No. 680,215.

To all whom it may concern:

Be it known that I, GEORGE C. CASSADA, citizen of the United States, residing at Galion, in the county of Crawford and 5 State of Ohio, have invented certain new and useful Improvements in Road Scarifiers, of which the following is a specification.

This invention relates to road scarifiers, 10 and particularly to those scarifiers wherein a transversely extending tooth carrying bar is disposed at the rear end of a tractor or road engine, means being provided for causing the depression or elevation of the bar 15 so that the teeth, when the tooth carrying bar is depressed, will drag through the road surface and operate to tear up the surface.

In machines of this character, the extent 20 to which the picks or teeth will enter the ground is controlled by means of gauge wheels which limit the downward movement of the tooth carrying bar.

One of the objects of the present invention is to provide a construction of this character wherein the gauge wheels are mounted directly upon the ends of the tooth carrying bar and extensions are provided of the tooth carrying bar which extend 30 laterally and rearward to a point behind the gauge wheels and carry scarifying teeth so that every portion of the roadway to the lateral edge, ditch or curbing will be scarified.

35 A further object is to provide a construction of this character wherein the extensions which support scarifying teeth behind the gauge wheels are removable from the main tooth carrying bar.

40 A still further object is to provide a construction of this character in which the lateral extensions heretofore referred to form part of the tooth clamping means of the main tooth carrying bar.

45 Another object is to provide means for supporting the lateral extensions of the main tooth carrying bar against the strain to which they are subjected and preventing their breakage or deformation under this strain.

50 Still another object of the invention is to provide a tooth carrying bar of the character stated wherein the gauge wheels are mounted directly upon said bar so as to move up and down therewith and so that

the gauge wheels shall be supported at that point where the bar and its operating means is subjected to the greatest stress by reason of the striking of the wheel against the pavement or roadway.

60 Other objects will appear in the course of the following description.

My invention is illustrated in the accompanying drawings, wherein:

65 Figure 1 is a fragmentary side elevation of the rear end of a road scarifier showing improved construction of the scarifying bar;

70 Figure 2 is a fragmentary rear elevation of the construction shown in Figure 1;

75 Figure 3 is a rear elevation of one end of the scarifying bar showing my attachment applied thereto, the picks being shown in section;

Figure 4 is a side elevation of the scarifying bar and the attachment, the rod 14 being in section;

80 Figure 5 is a top plan view of the pick carrying attachment.

85 Figure 6 is a fragmentary perspective view of the bar 17 and link 13 thereof and showing in dotted lines the manner in which the link 12 is engaged therewith.

90 Referring to these drawings, A designates a portion of the frame of a road engine, which may be of any suitable construction and be either gasoline driven or steam driven, the detailed construction of the road engine and the manner in which it is driven having no part in the present invention.

95 Pivotedly mounted on each side of the frame of the engine are arms 11 and 12, these arms being pivoted at their forward ends and extending slightly beyond the rear end of the tractor or road engine and being free to move up and down. Connecting the arms 11 and 12 are vertical links 13 which are integral with the scarifying bar 17. Passing through the forks or bifurcations 100 12^a of the arms 12 is a transverse rod or pin 14 which pivotally connects the vertical links 13 to the arms 12. The upper ends of the links 13 are pivotally connected to the arms 11 by means of the pins 15.

105 The transverse pin or rod 14 passes through a plurality of ears 16 formed upon the transversely extending tooth carrying bar 17, whose detailed structure will be later stated, and the extremities of the transverse 110

rod or pin 14 carry upon them the gauge wheels 18 which are intended to rest upon the surface of the roadway and travel therealong as the scarifier is drawn along the roadway. The links 13 are preferably in the form of arms extending from and practically integral with the tooth carrying bar 17.

For the purpose of raising and lowering the scarifying bar, a piston rod 19 is provided which operatively engages the bar 17 and which at its upper end carries a piston operating within a cylinder 20. This cylinder is pivotally mounted upon brackets projecting from the frame of the machine, and means is provided whereby compressed air, steam or other fluid under pressure may be admitted to the cylinder to raise or lower the piston rod 16. I have not illustrated the particular construction of the cylinder 20 or the manner in which it is mounted or the means whereby fluid is admitted to one end or the other of the cylinder for the purpose of raising or lowering the piston, inasmuch as these form no part of my present invention, and furthermore because any other suitable construction could be used for this purpose. The piston rod 19 is preferably pivoted to the bar 17 by means of transversely extending trunnions 21. Thus it will be seen that by the construction which I have described the teeth carried upon the bar 17 are always maintained at the same angular inclination regardless of their elevation so that the direction in which they are projected into the ground will be the same at all times or, in other words, the teeth are supported at the same inclination throughout their entire path of movement.

The tooth carrying bar 17 is preferably formed of an approximately T-shaped beam having an under surface which is disposed normally at an upward and rearward inclination. The lower edge of this bar is formed with a series of approximately V-shaped sockets 22, and coacting with the bar, and particularly with these sockets, are a series of pairs of clamping members 23, each formed with a V-shaped notch or socket in its face confronting the V-shaped notch or socket 22 of the bar 17. These clamping members 23 are engaged with the bar 17 by means of bolts 24 so that teeth or picks 25, which are approximately rectangular in cross section, may be disposed between the clamping members and the socket formed upon the pick carrying bar. These teeth may be adjusted inward or outward as desired and are held firmly clamped in place by the two sets of bolts 24. The two outside teeth at each end of the bar 17 are not held in place by the clamps 23 but are held in place by clamps which form part of a laterally extending pick carrying bracket or extension 26. This laterally ex-

tending bracket or extension is illustrated in detail in Figures 3 to 5. Each extension comprises a flat plate 27. The upper face of this plate is provided with a plurality of pairs of upwardly extending lugs 28 V-shaped in cross section to provide sockets coacting with the sockets 22 of the bar 17 and supporting the picks 25 therein. From the under face of this plate extends a web 29 which extends downward, rearward and laterally, as illustrated most clearly in Figure 5, the extremity of this web being disposed in a plane approximately parallel to the plane of the plate 27 and normally in a plane at an inclination to the surface of the roadway. This flattened extremity 30 is formed with the downwardly extending lugs 31, the inner faces of which are beveled so as to provide a V-shaped socket between the lugs, and coacting with this flattened end 30 are the clamping plates 32 which are also formed with V-shaped sockets in their upper faces and which are held in place to grip a tooth between the clamping plate and the flattened portion 30 of the bracket by means of the bolts 33. It will be seen that there are four of these bolts and two of the plates 32, and that the tooth or pick 25 will be firmly gripped in place between these lugs and held from any longitudinal or lateral movement.

The web 29 is formed with a laterally projecting, relatively deep rib 34 which is cut out at its middle, as at 35, to lighten the structure without reducing its strength. The web 29 is also formed with a downwardly depending lug 36 just below the web 34 and having an aperture for the passage of a rod or bolt 37. Each bolt 37 at its extremity is angularly bent at 38 and inserted in an aperture in the end lug of the T-bar or tooth carrying bar 17. The other end passes through the aperture 36 and is screw-threaded for engagement by nuts 39 and by a lock-nut 40 which will hold the supporting rod in firm engagement with the bracket.

This construction supports the end picks of the series of teeth or picks immediately behind and in alignment with the wheels 18 so that the roadway to the curbing, gutter line or to the extreme side of the road may be turned up and scarified. If the picks were not disposed behind the wheel 18, it is obvious that a portion of the roadway on each side adjacent the curb or gutter would have to be scarified by hand or separately. With this construction the operator can run the wheels 18 along the line of the gutter, curbing or road margin and at the same time be sure that the picks are scarifying the surface of the road to the extreme margin thereof. Furthermore, it will be seen that these lateral extensions are supported against strain not only by their

relatively heavy and rigid construction but by the supporting rods 37.

- It is also to be noted that the parallel motion which I have provided and which supports the picks at all times at a certain definite inclination without regard to whether the picks are elevated or depressed is particularly necessary where rearward extensions are used for the support of picks 10 immediately behind the wheels, as otherwise these picks so supported behind the wheels would strike the ground first and would enter more deeply into the ground than the picks immediately in front thereof. 15 Furthermore, the mounting of the wheels upon the transverse pin or rod 14 places these wheels in such position that they will more effectually sustain the shock of striking the ground than they would otherwise 20 do.

In the operation of this device, it will be seen that when the piston rod 16 is moved downward, the bar 17 will be moved downward, the arms 11 and 12 and the link 13 25 swinging upon their pivots and having a parallel motion which will maintain the picks or teeth at the same angular inclination regardless of their elevation. When the picks are forced downward they will 30 enter the ground in an inclined direction and owing to the fact that the whole mechanism is traveling along the ground, these picks will operate to tear up the surface, the gauge wheels, of course, engaging the 35 surface of the ground and controlling the depth of penetration of the picks so that the surface of the roadway to a uniform depth will be turned up. There is, of course, considerable strain upon the axles of these 40 gauge wheels but it is pointed out that the axle of the gauge wheel is very rigidly supported at intervals along the entire length of the tooth carrying bar and thus the structure will have sufficient rigidity to stand any 45 strain to which the mechanism is liable to be subjected. If for any reason it is not desired to use the lateral picks, that is those picks which are disposed behind the gauge 50 wheels, they may be readily removed and ordinary clamping devices such as shown at 23 and 24 used for the two end sockets of the pick-carrying bar to support the two end picks on each side.

While I have illustrated a construction 55 which has been found to be thoroughly effective in practice, which is strong, rigid and which will not give under the very heavy strain to which it is subjected, I do not wish to be limited thereto as it is obvious 60 that many details might be changed without departing from the spirit of the invention.

I claim:—

1. In a scarifier, a tooth carrying bar, arms pivoted at one end and pivotally connected at their opposite ends to said bar

and connected for parallel movement, a series of clamps mounted upon the tooth carrying bar, teeth supported by said clamps, gauge wheels associated with said bar and moving therewith and limiting the 70 downward movement of the bar, and members constituting detachable teeth clamps for the bar and extending laterally and rearwardly behind said wheels and having teeth 75 engaging clamps formed thereon.

2. In a scarifier, a tooth carrying bar mounted for vertical movement, means for forcing the bar downward, wheels operatively supported at the ends of the bar and limiting its downward movement, the bar 80 being formed to provide on its under face a series of tooth engaging sockets, clamping members coacting with these sockets, a bracket disposed at each end of the bar, the bracket being formed to provide a plate at 85 one end formed with tooth engaging sockets coacting with the end sockets of the bar, said bracket extending laterally, downwardly and rearwardly and at its extremity being formed to provide a plate having a tooth 90 engaging socket, clamping members coacting with the sockets on said plate and adapted to clamp a tooth in position between the extremity of each bracket and the clamping member, and a strain supporting member 95 operatively connected to each end of the bar and to each bracket adjacent the extremity thereof.

3. As an article of manufacture, a tooth holding bracket adapted to be used in connection with a tooth carrying bar, said bracket being formed to provide a plate at 100 one end adapted to confront the extremity of the scarifying bar and to provide a rearwardly, laterally and downwardly extending 105 web terminating in a plate-like member, means for engaging the first named plate to the extremity of the scarifying bar, and means for mounting a tooth upon the opposite end of said bracket whereby said tooth 110 may be supported rearward of a ground-engaging wheel.

4. The combination with a scarifier bar and means for elevating or depressing the bar, of a transversely extending rod mounted upon the scarifying bar and projecting beyond the ends of the same wheels mounted upon the ends of said rod, teeth mounted on the scarifying bar, brackets disposed at each end of the scarifying bar and detachably engaged therewith and extending downward and rearward to a point behind said wheels, means on the extremities of said brackets whereby teeth may be supported immediately behind said wheels, and a supporting rod for each bracket, each rod at one end being formed to engage the tooth carrying bar and at its other end having adjustable detachable engagement with the bracket.

5. The combination with a scarifier bar and means for elevating or depressing the bar, of a transversely extending rod mounted upon the scarifying bar and projecting beyond the ends of the same wheels mounted upon the ends of said rod, teeth mounted on the scarifying bar, brackets disposed at each end of the scarifying bar and detachably engaged therewith and extending downward and rearward to a point behind said wheels, means on the extremities of said brackets whereby teeth may be supported immediately behind said wheels, a supporting rod for each bracket, each rod at one end being formed to engage the tooth carrying bar and at its other end having adjustable detachable engagement with the bracket, the bracket having a perforated lug through which said rod passes, and nuts on the rod whereby the bracket may be rigidly engaged with the rod.
6. In a scarifier, a tooth carrying member, downwardly projecting teeth thereon, a rearwardly extending tooth carrying member carried by and movable with the main tooth carrying member, means for elevating and depressing the main tooth carrying member, and means for holding the main and rearwardly extending tooth carrying members always in such relation that the teeth carried thereby shall be always in the same horizontal plane and the teeth at the same angle to the ground throughout their path of movement.
7. In a scarifier, a tooth carrying bar, teeth thereon, means for raising and lowering said bar, rearwardly and laterally extending tooth carrying members mounted on the bar and movable therewith, and means for holding the tooth carrying bar in such position throughout its path of movement that the teeth carried thereby and by the rearwardly and laterally projecting members shall be always disposed in the same horizontal plane and at the same angle to the ground throughout their path of movement.

In testimony whereof I affix my signature.

GEORGE C. CASSADA.
